(57) **CLAIM**

The ornamental design for a gaming machine, as shown and described.

DESCRIPTION

FIG. 1 is a perspective view of a gaming machine showing our new design;

FIG. 2 is a front view of the gaming machine shown in FIG. 1;

FIG. 3 is a back view of the gaming machine shown in FIG. 1;

FIG. 4 is a left view of the gaming machine shown in FIG. 1;

FIG. 5 is a right view of the gaming machine shown in FIG. 1;

FIG. 6 is a top view of the gaming machine shown in FIG. 1; and,

FIG. 7 is a bottom view of the gaming machine shown in FIG. 1.

The broken lines shown in the FIGS. are provided for illustrative and environmental purposes only and form no part of the claimed design.

1 Claim, 4 Drawing Sheets
